UNITED STATES PATENT OFFICE.

DAVID E. PEPIN, OF WARE, MASSACHUSETTS, ASSIGNOR TO MASSACHUSETTS STREET RAILWAY AND PARK ASSOCIATION, OF PORTLAND, MAINE, A CORPORATION OF MAINE.

INTERCHANGEABLE TURNOUT FOR RAILWAYS.

SPECIFICATION forming part of Letters Patent No. 723,300, dated March 24, 1903.

Application filed April 5, 1902. Serial No. 101,559. (No model.)

To all whom it may concern:

Be it known that I, DAVID E. PEPIN, a citizen of the United States, and a resident of Ware, in the county of Hampshire and State of Massachusetts, have invented certain new and useful Improvements in Interchangeable Turnouts for Railways, of which the following is a specification.

In the usual method of constructing turnouts the casting which is included in the mate has formed integral therewith a rail-section which forms a part of the main track, and the main rail has therefore to have a section cut out in order to allow its insertion. This makes a waste of the portion cut out, and if for any reason the location of the turnout is changed it necessitates insertion of another short section of rail to complete again the main line. Another and very serious disadvantage of this cutting up the main rails is that it makes short joints, it being an advantage to have the fewest possible number of joints in the track.

The object of this invention is to provide such a form of mate that it can be connected at any part of the main line where desired and to utilize as a part of the combination those portions of the main rails which would ordinarily be cut off.

The invention will now be fully described by reference to the accompanying drawings, and the novel features thereof will be particularly pointed out in the claims at the close of the specification.

In the drawings, Figure 1 is a diagrammatic view of a section of railroad and turnout, illustrating the invention. Fig. 2 is a plan, partly in section, showing the mate and its connection with the rails.

Referring now to the drawings, 1 and 2 represent the two lines of rails forming the main track, and 3 4 represent the two lines of rails of the turnout.

The mate consists in part of a long casting the whole length of one side of which lies up against the web of the main rail 1 and the other side of which tapers for a part of its length, forming a somewhat wedge-shaped portion 5, which lies between the web of the main rail 1 and of the turnout-rail 3. The casting is formed with a shoulder 6 at the end

of the wedge portion 5 in front of the end of the turnout-rail. On the inner side of the turnout-rail 3 is a fillet 7, which fits up against the web of the rail 3 and the end of which makes a joint with the shoulder 6. A guard 9 extends alongside of the fillet 7 and the forward portion 8 of the casting. The guard 9 is a piece of flat steel. Bolts 10 pass through the guard 9 and the main rail 1 and all intermediate members—that is, at the wider portion they pass through the guard 9, fillet 7, turnout-rail 3, casting 5, and main rail 1. At the narrower portion they pass through the guard, casting, and main rail.

Turnouts constructed according to the invention can be built much more cheaply and with less labor than when the main rail has to be cut out to admit the ordinary special work, as heretofore done, and relocation of the turnout can also be much more economically made. Moreover, it obviates the necessity of short joints in the main track, which are very objectionable.

What I claim is—

1. In a turnout for railways, in combination with a main rail and a turnout-rail, a casting having a wedge-shaped portion between the main rail and the turnout-rail, a shoulder at the tapered end of the wedge-shaped portion which projects in front of the turnout-rail, an extension of the casting which lies against the web of the main rail, a casting which lies against the turnout-rail on the opposite side from the wedge-shaped portion, and which extends to said shoulder, and bolts which secure the castings and the rails together, substantially as described.

2. In a turnout for railways, in combination with a main rail, a turnout-rail, a fillet, a casting between the main rail and turnout-rail and extending beyond the end of the turnout-rail alongside of the fillet and the extension of the casting, all of said parts being secured together by bolts, substantially as described.

In testimony whereof I have affixed my signature in presence of two witnesses.

DAVID E. PEPIN.
